(57) **CLAIM**

The ornamental design for a hot tub tray, as shown and described.

DESCRIPTION

FIG. 1 is a perspective view of the set of a hot tub tray, showing my new design;

FIG. 2 is another perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is a partial enlarged view of FIG. 1;

FIG. 10 is a partial enlarged view of FIG. 1;

FIG. 11 is a partial enlarged view of FIG. 2;

FIG. 12 is a partial enlarged view of FIG. 2;

FIG. 13 is a partial enlarged view of FIG. 2; and,

FIG. 14 is a partial enlarged view of FIG. 2.

The broken lines in the drawings depict reference to the enlargements shown in the figures and form no part of the claim.
